(57) **CLAIM**

The ornamental design for a combined solar power bank and solar panel as shown and described.

DESCRIPTION

FIG. 1 is a front, right and top perspective view of a combined solar power bank and solar panel showing the new design;

FIG. 2 is a front, right and top perspective view of the solar power bank shown separated for ease of illustration;

FIG. 3 is a rear, left, and bottom perspective view thereof;

FIG. 4 is a front elevation view thereof;

FIG. 5 is a rear elevation view thereof;

FIG. 6 is a left elevation view thereof;

FIG. 7 is a right elevation view thereof;

FIG. 8 is a top plan view thereof;

FIG. 9 is a bottom plan view thereof;

FIG. 10 is a front, right, and top perspective view of the solar panel shown separated for ease of illustration;

FIG. 11 is a rear, left, and bottom perspective view thereof;

FIG. 12 is a front elevation view thereof;

FIG. 13 is a rear elevation view thereof;

FIG. 14 is a left elevation view thereof;

FIG. 15 is a right elevation view thereof;

FIG. 16 is a top plan view thereof;

FIG. 17 is a bottom plan view thereof; and,

FIG. 18 is an enlarged view of detail 18 in FIG. 2.

The dashed broken lines depict portions of the combined solar power bank and solar panel that form no part of the claimed design. The dot-dash broken lines in FIGS. 1 and 18 depict the boundaries of the enlarged views and form no part of the claimed design.

1 Claim, 18 Drawing Sheets
